UNITED STATES PATENT OFFICE.

HEINRICH LUDEWIG, OF CHARLOTTENBURG, GERMANY.

ROTARY OR CENTRIFUGAL PUMP OPERATING WITH AUXILIARY TURBINES.

No. 879,059.

Specification of Letters Patent.

Patented Feb. 11, 1908.

Application filed April 24, 1905. Serial No. 257,263.

To all whom it may concern:

Be it known that I, HEINRICH LUDEWIG, a subject of the German Emperor, residing at No. 7 Spandauerstrasse, Charlottenburg, near Berlin, in the German Empire, professor of the Königlichen-Technischen Hochschule in Berlin, have invented certain new and useful Improvements in Rotary or Centrifugal Pumps Operating with Auxiliary Turbines, 10 of which the following is a specification.

In centrifugal pumps in which the pump disk leads directly into the end of the casing connected to the rising main the absolute velocity of delivery of the pressure fluid is mostly lost by concussion and formation of eddies; with heights of lift that are not very small the velocity is considerable at the commencement, while the velocity in the conduit pipes should not exceed one or two 15 meters per second, even with considerable lifts. This loss of speed can, under certain circumstances, be reduced by means of fixed guide blades arranged around the pump wheel in the known manner. This, however, necessitates the condition that the pump wheel shall only be driven at a certain favorable number of revolutions, *i. e.* with a certain peripheral velocity, in order that the pressure against the fixed guide blades may 20 be avoided. By means of the guide blades the speed of the discharge water from the pump wheel into the cells of the guide ring is to be converted into pressure of the water, in consequence of the gradual alteration of 25 the sectional area of the cells, as the pressure, of the water in the cells of the guide ring, increases in proportion to the decrease of speed. This assumption, however, as shown by experiments is only correct to a very 30 limited degree, for, even with the most careful determination of the sections of the cells, there generally occurs almost as great a loss as with a sudden change of section (see *Civil Ingenieur* 1878, page 98, *Schweizerische 35 Banzeitung* Vol. 42, No. 8, *Fliegener "Ein neuer Weg zur Berechnung der Starkurve"* Zeitschrift für das gesamte Turbinenwesen 1906 pages 12 to 14). According to the 40 present invention such losses of energy are entirely avoided by arranging beyond the guide ring of the pump an auxiliary turbine which acts as motor and converts the kinetic 45 energy of the fluid into energy of rotation, which is transmitted back to the pump shaft

so that the external driving power for the 55 pump for raising the liquid to a certain height is correspondingly reduced.

In the accompanying drawings are shown 60 various modes of construction for carrying out the said invention.

Figure 1 shows a longitudinal section of the combined pump guide ring and turbine; Figs. 2 and 3 show diagrammatic cross sections thereof; Fig. 4 shows a similar construction adapted to a compound pump; Figs. 5 and 6 65 show a longitudinal section and part cross section of a modification in which the guide passages are formed with a double curvature so that the turbine acts with an outward flow. 70

Fig. 1 shows a vertical section of an arrangement in which a pump disk P is combined with a turbine disk T there being arranged between the two disks P and T a fixed ring of guide blades L. In this case P 75 and T are connected together by one and the same boss so as to form a single rotating body; the pump disk and the turbine disk can, however, be constructed as separate bodies. By means of the guide ring L inter- 80 posed between the pump disk P and the turbine disk T and abutting directly against these, the pressure fluid issuing from P with the velocity C_a (Fig. 2) is led as impact fluid to the turbine and issues at the end of the 85 guide ring (Fig. 3) with the absolute velocity c' into the turbine wheel, in order, there, to perform work. After the impact fluid of the auxiliary turbine has imparted to this the greater part of its energy it will in leaving 90 the turbine with the speed c'_a pass directly into the rising main of the pump. The construction of the auxiliary turbine must therefore be such that it acts only as turbine motor and not also as pump, increasing the pressure. 95

If the liquid pressures, in front of and behind the turbine wheel are to remain equal the auxiliary turbine must act as a so-called "equal pressure turbine", which has only to convert the kinetic energy of the fluid into 100 energy of rotation as absolute impact head. Also, within the guide channels of the guide ring any alteration in the pressure of the liquid passing through has to be avoided. The interposed guide ring is therefore to be 105 constructed (in contradistinction to the construction of the ordinary guide rings applied beyond the pump disk) with enlargement of

the section of the guide passages in such manner that $c_a = c'_e$. Leaving out of consideration any unavoidable guide or friction resistance, the pressure at the outlet of the pump 5 disk at the radius r_a will be the same as in front of the turbine wheel at the radius r'_e and beyond the turbine wheel at the radius r'_a . Consequently the pump has to be calculated in the same way as with the old construction of pump without rear guide ring as though the kinetic energy of the fluid were almost entirely lost by impact against the pump casing. This apparent loss is returned 10 by means of the auxiliary turbine the more so the higher is the efficiency of the auxiliary turbine. To effect this the inlet radius r'_e of the auxiliary turbine is chosen smaller than the outlet radius r_a of the pump wheel. The advantage of this is shown from the following. The impact speed c'_e corresponds, with 15 a smooth motion of the turbine, to a certain peripheral velocity v'_e of the turbine wheel. Consequently v'_e is dependent upon the peripheral velocity v_a already determined, of 20 the pump. The wheels P and T being arranged on one and the same shaft have the same speed, so that $v'_e/v_a = r'_e/r_a$. According to the known rules of turbine construction it is of advantage, for obtaining a good 25 useful effect, if the peripheral speed v'_e is smaller than c'_e viz. only about half as great, but as c'_e is made equal to c_a , consequently v'_e is smaller than c_a . With the pump wheel, according to the choice of the angle of the 30 blades and the speed of the pump, the absolute speed of issue c_a of the pressure water is dependent upon the chosen peripheral speed v_a of the pump wheel.

In order to keep the friction losses for 40 water small in the guide ring with a great c_a it is of advantage to make c_a smaller than v_a , which may be attained by a suitable choice of the angle of the pump blades. With v'_e smaller than c_a , and c_a smaller 45 than v_a , it follows that v'_e is smaller than v_a . But the condition that v'_e is to be smaller than v_a is attained by making r'_e smaller than r_a . This condition which determines the dimensions of the inlet and outlet radii of the intermediate guide ring is therefore an essential feature of the invention. Consequently in the construction 50 shown at Figs. 1, 4, 5 and 6 the inlet radius r'_e is made smaller than the outlet radius r_a of the pump disk. As shown in Fig. 1 the guide ring and the turbine ring of the auxiliary turbine can be so arranged that the issuing water is led off in axial direction directly into the rising main. This arrangement is also facilitated by the fact that r'_e 55 must be chosen smaller than r_a and consequently the outlet radius r'_a of the turbine wheel can also be made so small that the outlet is situated directly around the shaft.

60 65 With such axial discharge of the liquid from

the turbine the improved pump construction is rendered suitable for the combined construction of several pumps in the form of a compound pump, as shown in vertical section in Fig. 4, as in this case the liquid issuing 70 axially from the auxiliary turbine can be led directly to the inlet of the next pump disk.

If the auxiliary turbine is constructed for equal pressures of the inlet and outlet liquid, it can be constructed according to the usual 75 forms of equal pressure turbines, either as axial or as radial turbine. If an outward-flow radial turbine be chosen then, as shown in Figs. 5 and 6, the water issuing from the turbine is led through an annular collecting 80 channel to the rising main of the pump, which is in that case arranged at the side of such channel. For enabling such an arrangement to be used, the guide ring L must be formed with a double curvature, as 85 shown.

The intended advantage of the new construction over pumps of known construction with guide ring can only be attained if the auxiliary turbine acts with good useful 90 effect. It is, however, known that the equal pressure turbines are inferior as regards the useful effects obtained in comparison with turbines operating with fall of pressure (reaction or excess pressure turbines) as is 95 shown by the present general adaptation of the Francis turbine as excess pressure turbine, that is, with fall of pressure, which, as is known, is effected by a proper choice of the angles of the blades, and in particular 100 of the cross sections of the passages of the turbine wheel. In this particular case the water pressure at the line of the turbine radius r'_e is arranged to be greater than that at the discharge radius r'_a . In consequence 105 of the condition $c_a = c'_e$ the water pressure at the line of radius r_a is as great as at the line of radius r'_e . Consequently in this case the pump must be calculated as though it were intended for a greater lift, and therefore the 110 velocity c_a and the kinetic energy of the fluid must also be greater, but the greater amount of rotary work requisite for this purpose is regained in the turbine with particularly good useful effect, so that the total useful 115 effect of the pump having the reaction turbine is increased as compared with a pump with equal pressure turbine. To this improvement in the useful effect has to be added the fact that the excess pressure turbine can 120 be constructed in the same way as the usual form of Francis turbine of American construction, whereby practical advantages in the construction are obtained.

Having now particularly described and ascertained the nature of my said invention and the best means I know of carrying the same into practical effect, I claim:

1. In an apparatus of the class set forth, a centrifugal pump, with an auxiliary turbine 130

- operating as motor mounted on the same shaft and revolving at the same speed as the pump, and a fixed guide ring interposed between the outlet of the pump and the inlet of the turbine, the radius of the outlet of the pump and inlet of said guide ring being greater than the radius of the outlet of the guide ring and inlet of the turbine, substantially as described.
10. 2. In an apparatus of the class set forth, a centrifugal pump, with an auxiliary turbine operating as motor mounted on the same shaft and revolving at the same speed as the pump, and a fixed guide ring interposed between the outlet of the pump and the inlet of the turbine, the radius of the outlet of the pump and inlet of said guide ring being greater than the radius of the outlet of the guide ring and inlet of the turbine, and the outlet of the turbine being arranged to immediately surround the pump shaft so that the liquid issues therefrom in the axial direc-

tion substantially as and for the purpose described.

3. In an apparatus of the class set forth, a 25 centrifugal pump, an auxiliary turbine operating as motor with drop of pressure (reaction turbine) mounted on the same shaft and revolving at the same speed as the pump, and a fixed guide ring interposed between 30 the outlet of the pump and the inlet of the turbine, the radius of the outlet of the pump and inlet of said guide ring being greater than the radius of the outlet of the guide ring and inlet of the turbine, substantially 35 as described.

In testimony whereof I have signed my name to this specification in the presence of two subscribing witnesses.

HEINRICH LUDEWIG.
